CLAIM

The ornamental design for a joystick control unit, as shown and described.

DESCRIPTION

FIG. 1 is a front side view of a first embodiment of a joystick control unit;

FIG. 2 is a front perspective view of the first embodiment;
FIG. 3 is a front side view of a second embodiment of a joystick control unit;

FIG. 4 is a front perspective view of the second embodiment;
FIG. 5 is a front side view of a third embodiment of a joystick control unit;

FIG. 6 is a front perspective view of the third embodiment;
FIG. 7 is a front side view of a fourth embodiment of a joystick control unit;

FIG. 8 is a front perspective view of the fourth embodiment;
FIG. 9 is a back side view of the first, second, third, and fourth embodiments;

FIG. 10 is a left side view of the first, second, third, and fourth embodiments;

FIG. 11 is a right side view of the first, second, third, and fourth embodiments;

FIG. 12 is a top side view of the first, second, third, and fourth embodiments;

FIG. 13 is a bottom side view of the first, second, third, and fourth embodiments; and,

FIG. 14 is a rear perspective view of the first, second, third, and fourth embodiments.

The areas in broken lines are for illustrative purposes only and form no part of the claimed design.

The drawings of FIGS. 1, 2, 3, 4, 5, and 6 are lined for the color red.
